UNITED STATES PATENT OFFICE.

ALBERT F. AMMAN, OF NAPONEE, NEBRASKA.

FIRE-ESCAPE.

1,158,952.

Specification of Letters Patent.

Patented Nov. 2, 1915.

Application filed August 17, 1914. Serial No. 857,081.

To all whom it may concern:

Be it known that I, ALBERT F. AMMAN, citizen of the United States, residing at Naponee, in the county of Franklin and State of Nebraska, have invented certain new and useful Improvements in Fire-Escapes; and I do hereby declare the following to be a full, clear, and exact description of the invention, such as will enable others skilled in the art to which it appertains to make and use the same.

This invention relates to improvements in fire escapes, and has particular reference to individual portable fire escapes of that type in which a flexible cable is employed as a support and track-way for a traveling carrier.

The invention has for its principal object a simplified construction of individual portable fire escapes, while retaining or supplying all of the positive qualities of safety and ease of operation which are necessary for the rapid and efficient rescue of persons in peril in the upper stories of buildings during times of fire.

Where fire escapes are furnished which are intended for use and operation by individuals in order to rescue themselves from buildings, it is essential that the devices be of such a simple nature, and of such simple operation that even those persons who are laboring under the stress of excitement will find the apparatus easily operated and will be assured by its operation that they may safely descend from the building.

A further object of the invention is to provide a fire escape of the individual type above mentioned which is always in a position for immediate use. That is to say, in the actual use of devices of this kind, it would prove difficult and a decided disadvantage if it is necessary to return the movable element upon the supporting cable in case a second party desires to use the fire escape after the descent of a former user.

In order to avoid this disadvantage, the carrier is provided of such construction that the whole cable may be reversed, and when this is done the carrier will still be found in such a position that a succeeding user may immediately descend.

With the above, and other objects which

will hereinafter appear, in view, my invention will be fully described, reference being had to the accompanying drawings, in which,

Figure 1 is an elevation, partly in section, of the apparatus in position for use. Fig. 2 is a section on line 2—2 of Fig. 1, and Fig. 3 is a section on line 3—3 of Fig. 1.

Referring now more particularly to said drawings, 1 represents a section of a flexible cable of any suitable material which may be coiled and suitably disposed at an interior or exterior point adjacent the window or other opening in a building from which inmates of the building are intended to escape in case of fire.

A pair of substantially identical members 2 form the body of a carriage or carrier which is slidable on the cable 1, each of the members 2 consisting of a comparatively long narrow block of metal, wood, or suitable material, which is provided on one edge or narrow side with a plurality of alternate elevations and depressions giving the side a substantially scalloped or tortuous contour. Following the contour of the tortuous edges of each block 2 is a groove 3 of uniform depth which provides a slideway for the cable 1. When the blocks 2 are contiguously mounted to form the body of the carriage, the elevations of the contoured side of one block coincide with the depressions of the contoured side of the opposite block. Inasmuch as the semi-annularly shaped grooves 3 are formed of uniform depth throughout the lengths of the contoured sides of the blocks, the coincidence of the blocks as above described forms a zig-zag passage-way for the cable 1, the body of the carriage incasing the cable throughout the length of the passage.

The two members 2 are adjustably yoked together by means of brackets or arms 4, links 5 and connecting operating devices. The arms or brackets are rigidly secured to their respective blocks 2 at opposite ends of the carriage, the arms of each block being arranged in pairs which are secured opposite one-another on the faces of the blocks 2, as indicated in Fig. 2. The links 5 of each block are pivotally mounted thereon, with their pivot points adjacent the points

of attachment of the arms or brackets 4, but upon the opposite blocks as indicated at 6, and extending in substantially parallel relation to said arms or brackets 4. It will be noted that the links 5 are pivoted above and below the upper and lower arms or brackets 4, respectively. Controlling or operating levers 7 are journaled between free ends of the arms or brackets 4 of each block 2, said levers 7 being provided with bosses 8 at intermediate points 9 through which shafts or bolts 10 extend for the purpose of providing bearings for the levers 7 between the arms 4. The short arms of the levers 7 are pivotally connected to the respectively adjacent pairs of links 5, the bearings being provided by the passage of bolts or shafts 12 through the bosses 11 and the free ends of the links 5, as indicated in Fig. 3.

It will be noted from the description thus far given that the opposite ends of the carriage are identical in construction and that the two operating levers 7 extend in opposite directions parallel to, and in substantially close relation to, the carriage. Equal movement of the free ends of the levers 7, which are formed as hand-grips, will move equally the opposite ends of the carriage toward or from the cable 1, according to the direction of such movement of the hand-grips.

At both the upper and lower ends of the carriage, the latter is provided with rings or clips 13, which, in the present construction, are shown as U-shaped elements having their ends bolted on opposite sides or faces of the blocks 2. The rings 13 are provided for the attachment of suitable supporting or saddle devices, which, in the present instance, are represented as straps or yokes 14 which are adapted to incase the legs of the user, each of the straps 14 being removably attached to the rings 13 of that end of the carriage which at the time is lowermost. Spring clips 15 secured to the yokes or straps 14 are provided for the removable attachment of the latter to the rings 13.

The ready detachability of the straps or yokes 14, or whatever other supporting device is used, plays an important part in the successful operation of the present device. Assuming that the carriage has been lower on the cable 1 with an occupant, and that a second person on one of the upper floors of a building desires to use the fire escape, it is unnecessary, with the apparatus constructed according to my invention, to raise the fire escape on the cable. On the other hand, the carriage is allowed to remain on the lower end of the rope or cable, and the whole cable is reversed end for end by hand or in other suitable manner until the carriage is thus brought again to the upper level, when the yoke or straps are detached from what is then the upper end of the car-

riage and snapped in position on the lower end of the carriage, thus bringing into use the second set of rings 13.

The operation of my apparatus having been set forth in substantially full degree 70 during the description thereof, a separate discussion of its use is not now deemed necessary.

It is evident that the present invention provides a simple and effective emergency 75 rescue apparatus for use by individuals who may be caught in the upper stories of a burning building, and that the device may be compactly and handily located in position for use adjacent a suitable window or 80 other opening, from which it may be readily suspended for use.

Having thus described the invention, what I claim as new, and desire to be secured by Letters Patent, is:—

1. A fire-escape, comprising in combination, a supporting cable, a carriage consisting of blocks incasing said cable and movable toward and from the latter to regulate the grip thereon, and means for actuating 90 said blocks, said actuating means consisting of levers each of which is fulcrumed on one block and linked to the other at one end of the carriage, said levers also extending in opposite and overlapping relation to permit 95 the operation of either end of the carriage from any part of the latter.

2. A fire-escape, comprising in combination, a supporting cable, a carriage consisting of blocks incasing said cable and providing a passage way for the latter, and means for moving said blocks toward and from the cable to regulate the grip on the latter, said means comprising levers each of which is fulcrumed on one block and linked 105 to the other at the end of the carriage, said levers also extending substantially along the entire sides of said carriage in substantially parallel relation thereto to permit the operation of either end of the carriage from any 110 part of the latter.

3. A fire-escape, comprising in combination, a carriage consisting of oppositely disposed blocks forming a passage way therebetween, a cable extending through said passage way to permit movement of the carriage thereon, and actuating means on said carriage for regulating the grip of said blocks on the cable, said actuating means consisting of a pair of levers, each of which 115 is fulcrumed adjacent the end of one block and linked to the corresponding end of the opposite block, said levers also extending in substantial parallelism to each other and to the carriage to permit the regulation of the 125 grip of either end of the carriage upon the cable from any part of the carriage.

4. A fire escape, comprising in combination, a supporting cable, a carriage movable on said cable from end to end, and consist- 130

ing of oppositely disposed blocks incasing said cable and movable toward and from the latter, identical sets of linked connections at opposite ends of the carriage for spreading the blocks, hand levers for actuating said linked connections disposed in such relation as to render the carriage equally operable from either end, and supporting

yokes attachable to either end of said carriage.

In testimony whereof I affix my signature, in the presence of two witnesses.

ALBERT F. AMMAN.
